UNITED STATES PATENT OFFICE.

JOSEPH WILLMANN, OF DERBY, CONNECTICUT.

REGENERATIVE PASTEURIZER.

986,257.

Specification of Letters Patent.

Patented Mar. 7, 1911.

Application filed April 9, 1909. Serial No. 488,925.

To all whom it may concern:

Be it known that I, JOSEPH WILLMANN, a subject of the Emperor of Germany, residing at Derby, in the county of New Haven and State of Connecticut, have invented new and useful Improvements in Regenerative Pasteurizers, of which the following is a specification.

My present invention relates to improvements in pasteurizers of the class used in pasteurizing milk, cream and other liquids, and it has for its object primarily to provide an improved pasteurizer of the regenerative type whereby a relatively high efficiency in the preliminary heating of the entering liquid and the cooling of the outflowing liquid is attained, the uniform exposure of the liquid to the heating medium without overheating is insured, and preferably the operation of certain parts of the pasteurizer serves to automatically transfer the heated liquid from the heating chamber to the regenerative chamber.

Another object of the invention is to provide a pasteurizer of this class the construction of which enables the parts or elements to be taken apart with the greatest facility for cleansing and sterilization and to be again assembled readily.

A further object is to provide a regenerative section for the pasteurizer which is of an improved construction, it presenting a relatively large aggregate area within a given space to the liquid during the mutual heating and cooling thereof, its elements may be readily taken apart and reassembled and when assembled, this section of the pasteurizer may be readily applied or removed as a unit with reference to the heating section of the pasteurizer.

To these and other ends, the invention consists in certain improvements, and combinations and arrangements of parts, all as will be hereinafter more fully described, the novel features being pointed out particularly in the claims at the end of the specification.

In the accompanying drawings—Figure 1 represents a central vertical section of a regenerative pasteurizer constructed in accordance with my present invention; Fig. 2 is a detail sectional view of a portion of the apparatus showing one of the blades for in-

ducing a flow of the heated liquid from the heating chamber to the regenerative section; 55 and, Figs. 3 and 4 are detail views of the element for insuring uniform exposure of the liquid to the heating medium, preventing sticking of the liquid upon the walls of the heating chamber and for causing the 60 discharge of the liquid from the heating chamber.

Similar parts are designated by the same reference characters in the several views.

My present invention is applicable generally to regenerative pasteurizers and in the accompanying drawing, I have shown one form of the invention. It will be understood, however, that the form shown in the drawing is illustrated as an example, as 70 certain modifications or changes may be made in the apparatus in order that the invention may be applied to the best advantage in each particular case as circumstances may require. 75

The pasteurizer shown in the accompanying drawing comprises generally a heating jacket 1 which in this instance is annular and is inclosed by the inner and outer walls 2 and 3, the bottom of this jacket being 80 closed by a plate 4 which may form the top of an appropriately constructed base 5, steam or other suitable heating medium being conducted preferably to the upper portion of the heating jacket by an inlet pipe 6, and it may be exhausted together with any water of condensation by the outlet pipe 7. The top of the heating jacket is closed by an annular casing 8 which forms an annular channel 9 within it, the top of this 90 channel being bounded by an inwardly projecting or overhanging wall 10 of the casing.

The regenerative section of the pasteurizer according to the present invention is bodily removable as a unit with reference to the 95 heating section which has just been described as supported on the base. In the present instance, I have shown a regenerative section which is of an improved construction, it consisting of an outer corrugated cylinder 11 and an inner corrugated cylinder 12, these cylinders being of different diameters so that one may readily fit within the other, and the space between their walls forms a chamber 13 through which the 105 liquid after leaving the heating chamber

passes before it is finally discharged. The fresh liquid entering the apparatus preferably flows downwardly over the corrugated walls of the two cylinders, and for this purpose, the outer cylinder is provided with a gutter 14 which projects outwardly from its upper portion and is provided with suitable openings 15 through which the liquid entering this gutter from the pipe 16 may pass and then flow downwardly over the exterior wall of the outer cylinder, a casing 17 preferably surrounding the outer cylinder so as to protect the liquid under treatment and to also serve as means for the attachment of a supporting flange 18 which is suitably secured to this casing and is adapted to rest upon the top of the casing 8 of the heating section. In order to insure a fluid-tight fit between the regenerative and heating sections of the pasteurizer, an annular packing strip 19 may be interposed between the upper wall 10 of the casing 8 and the flange 18, and to secure the parts in position, a suitable number of clamping bolts 20 may be provided, these bolts being such that they may be readily manipulated to fasten or unfasten the two sections as may be desired. The inner cylinder 12 is also provided with a gutter 21 to which the liquid is conducted by a second pipe 22, the bottom of the gutter 21 being provided with suitable openings 23 through which the liquid may pass and then flow downwardly over the interior wall of the inner cylinder. In the present instance, the liquid to be treated is supplied to the pipes 16 and 22 by a tank 24. In order to connect the inner and outer cylinders of the regenerative section in such a way that they may be readily separated for cleansing or sterilization while at the same time they may have a liquid-tight fit between them, the upper portion of the inner cylinder is provided in the present instance with an external flange 25 which co-operates with a corresponding flange 26 on the outer cylinder preferably through the medium of a packing ring 27 which is interposed between such flanges while the bottom of the inner cylinder is provided with an internal ring 28 and the outer cylinder is provided with a corresponding internal ring 29, these rings being drawn together by means of a suitable number of bolts or equivalent devices 30. Preferably the same means which draws together the rings at the lower ends of the cylinders serves to produce the liquid-tight joint between the upper portions of these cylinders, and in order to prevent leakage of the liquid at the lower ends of the cylinders, one of the rings in the present instance is provided with a tapered rib 31 which closely fits a correspondingly shaped groove in the other ring.

When the regenerative section is mounted

within the heating section of the pasteurizer, 65 a chamber is formed between the two sections wherein the liquid to be treated is heated, the liquid entering this heating chamber after flowing downwardly over the corrugated walls of the two cylinders of the 70 regenerative section. In order to insure uniform exposure of all portions of the liquid to the effect of the heating jacket 1 so that the dangerous bacteria may be killed or rendered harmless, I prefer to use mechanical 75 means for maintaining an agitation of the liquid so that all portions may be brought into contact with the inner wall of the heating jacket. At the same time I provide means for preventing sticking or burning of 80 the liquid upon the inner wall of the heating jacket. The means shown in the present instance for accomplishing these results consists of a revolving element which comprises a yoke-shaped frame which has arms 32 85 which are rigidly attached to and extend upwardly from a base section 33, these arms each carrying preferably a plurality of independently movable scrapers 34 which, however, may be pivoted on a common pivot 90 rod 35, the independent arrangement of these scrapers enabling them to closely fit and bear against the inner wall 2 of the heating jacket irrespective of any irregularities that may exist. These arms and the 95 scrapers carried thereby are of such dimensions that they may revolve freely between the heating jacket and that portion of the regenerative section which depends into the heating jacket, the resistance offered by the 100 liquid within this chamber serving to automatically press the scraper blades against the inner wall of the heating jacket. In order that this revoluble element may be used for creating the discharge of the liquid from 105 the heating chamber after it has been exposed for the proper period, blades 36 are arranged on the arms of the revoluble element and they operate within the annular channel 9 formed in the casing 8, and this 110 channel is provided with an outlet or exit 37 which preferably leads tangentially from its periphery, the centrifugal effect produced by the rotary motion of the liquid in the channel 9 under the influence of the 115 blades 36 causing such liquid to be discharged through said exit, and liquid to replace that discharged in this manner is drawn from the lower portion of the heating chamber through the operation of these 120 centrifugal blades. In order to permit the revoluble element to be bodily removed from the heating section of the pasteurizer, these blades 36 are preferably pivoted to the arms so that they may be swung inwardly to clear 125 the overhanging wall 10 of the casing in which they operate, lugs or shoulders 38 being provided to serve as rests to support

these blades in outstanding position while in operation.

To further facilitate the removal of the revoluble element, the latter is provided in the present instance with a centrally arranged socket 39 which receives a suitable operating shaft 40, this shaft having preferably a spline connection with the socket so that the latter may be applied to and removed from the upper end of this shaft although a driving connection is provided between them. The shaft 40 in the instance shown extends upwardly through the top plate of the base, a suitable packed joint being provided if necessary, and motion may be transmitted to this shaft to effect the necessary movement of the revolving element, a tight and loose pulley arrangement being shown as an instance in the drawing.

20 A pipe 41 connects the outlet 37 of the heating section to the inlet 42 arranged preferably at the bottom of the regenerative section, and the latter in the present instance is provided with an outlet 43 which may be connected to a suitable cooler. A ring 44 preferably connects the arms of the revoluble element to retain them in proper relation.

The operation of the pasteurizer shown in the present instance may be briefly described as follows: The milk or liquid to be pasteurized is supplied to the apparatus by the upper tank from which the liquid flows into the troughs and thence over the corrugated walls of the inner and outer cylinders of the regenerative section. As the heated liquid leaving the apparatus after pasteurization passes through the chamber formed between these cylinders, such liquid will give up its heat to the relatively cooler liquid entering the apparatus, the entering liquid being thereby preliminarily warmed while the discharging liquid is cooled appreciably. From the regenerative section the liquid thus warmed enters the heating chamber which is under the influence of the heating jacket, and while in this heating chamber, the temperature will be uniformly increased to the pasteurizing point owing to its contact with the wall of the heating jacket and the constant agitation of the liquid due to the action of the revoluble element, the scraper blades thereon performing the dual function of keeping the liquid in motion so that different portions thereof are being exposed to the direct heat of the jacket, and sticking and consequently overheating of the liquid is avoided. When the liquid reaches the upper portion of the heating chamber, it is acted on by the revolving blades, the centrifugal effect thus produced causing the liquid to discharge from the heating section and it is then conveyed to the lower portion of the regenerative section, this liquid at a

relatively high temperature then ascending 65 through the space between the cylinders where its temperature is lowered by the liquid entering the pasteurizer.

I claim as my invention:—

1. A regenerative pasteurizer comprising 70 a heating section and a regenerative section, the regenerative section being removably mounted within the heating section.

2. A regenerative pasteurizer comprising a heating section, a regenerative section, and 75 means for removably supporting the regenerative section within the heating section.

3. A pasteurizer comprising a heating section, a cooling section, the cooling section adapted to be contained by the heating section, and means for detachably connecting 80 said sections and forming a fluid-tight joint between them.

4. A pasteurizer comprising a heating section, a regenerative section composed of 85 relatively separable members, the regenerative section being capable of application and removal as a unit within the heating section.

5. A regenerative pasteurizer comprising a heating section, a regenerative section, 90 said sections being arranged at different elevations and provided with means for conducting liquid from one to the other, and means operable within the heating section for inducing a flow of liquid from the lower 95 to the upper section.

6. A pasteurizer comprising heating and regenerative sections arranged at different elevations and having means for conducting liquid from one to the other, and means to 100 act upon the liquid in the heating section to produce a centrifugal action that will cause a discharge of the liquid from the heating section and into the regenerative section.

7. A pasteurizer comprising a heating 105 section, a regenerative section depending into the heating section and communicating with a heating chamber in the latter, and a revoluble element contained within said heating chamber and having means to act 110 centrifugally upon the liquid therein to cause its discharge into the regenerative section.

8. A pasteurizer involving a heating section forming a heating chamber for a liquid, 115 and a revoluble element having scraping blades to coöperate with the walls of the heating chamber, each blade being composed of a plurality of superposed independently movable sections to coöperate with and conform to the shape of the wall of the heating chamber.

9. In a pasteurizer, the combination of a heating section forming a chamber for the liquid to be pasteurized, the upper portion 125 of said chamber communicating with an annular outwardly offset channel having an outlet, a revoluble element having a blade to

operate in said channel and to effect a discharge of liquid from the heating chamber by centrifugal action, and a regenerative section mounted within said heating section 5 and removable therefrom as a unit, the regenerative section having an inlet connected to receive the liquid discharged from the heating section.

10. In a pasteurizer, a heating section forming a heating chamber for the liquid to be pasteurized, an annular channel offset outwardly from said chamber and communicating with said chamber, a revoluble element mounted in said chamber and having 15 scrapers to coöperate with the walls thereof, said revoluble element also carrying a freely movable blade which is operable in said channel to effect a discharge of liquid from the heating chamber, and a regenerative section extending to a height above the heating section and having a lower inlet to receive liquid discharged therefrom and having an outlet above the heating section.

11. A regenerative pasteurizer comprising 25 an outer heating section, a regenerative section depending into the interior of the heating section and connected to receive heated liquid therefrom, and a revoluble element mounted within the heating section and embodying a plurality of upwardly extending 30 arms having scrapers thereon to coöperate with the walls of the heating section, said arms and scrapers operating in an annular space formed between the heating and regenerative sections, and a ring surrounding 35 the regenerative section and rigidly connecting the upper ends of said arms.

12. In a regenerative pasteurizer, the combination of a heating chamber for the liquid 40 to be pasteurized, a regenerative section having its lower end depending into the interior of the heating chamber, means connecting the heating chamber to the regenerative section whereby the latter may receive heated 45 liquid from the heating chamber and having a plurality of arms extending upwardly into an annular space formed between the heating chamber and the regenerative section, said arms being provided with scrapers to 50 coöperate with the walls of the heating chamber and also carrying blades operative to discharge the heated liquid centrifugally from the heating chamber, and a ring surrounding the regenerative section and rigidly connecting the upper portions of said arms.

13. A regenerative pasteurizer comprising 55 a heating section provided with a jacket for a heating medium and a chamber for the liquid to be pasteurized, the upper portion of said chamber being open, a regenerative section adapted to enter the heating chamber and extend to an elevation higher than the top of the heating section, and a flange

attached to the regenerative section and 65 serving to support the same within the heating section and to produce a fluid-tight closure for the top of the heating chamber.

14. A regenerative section for pasteurizers comprising members each interiorly and exteriorly corrugated and adapted to be mounted one within the other and to form a liquid passage between them, means on opposite ends of said members for detachably uniting them, and means on each member for causing the flow of liquid over its respective exterior corrugated surface.

15. A regenerative section for pasteurizers comprising relatively separable inner and outer members forming a liquid passage between them, means for producing a fluid-tight connection between both ends of said sections, and a gutter formed on each member for causing a flow of liquid over its respective exterior surface.

16. A regenerative section for pasteurizers comprising two interiorly and exteriorly corrugated members one removably mounted within the other, coöperative pairs of rings at both ends of said members for producing fluid-tight joints between them, and means at one end of the section for detachably uniting the rings at both ends thereof.

17. A regenerative section for pasteurizers comprising separably connected inner and outer members forming a passage to contain liquid between them, and means formed on the respective members for causing a fluid to descend in films over the inner wall of the inner member and the outer wall of the outer member, and an inlet on one member and an outlet on the other member for conducting liquid to and from the passage formed between the members.

18. A regenerative section for pasteurizers comprising corrugated members one removably contained within the other and forming a liquid passage between them, a gutter for discharging a liquid over the exterior wall of the outer section, a gutter for causing the flow of a liquid over the interior wall of the inner member, and an inlet carried by one member and an outlet carried by the other member for conducting liquid to and from the passage formed between the members.

19. A regenerative pasteurizer comprising a heating section providing a heating chamber for the liquid to be pasteurized, a regenerative section comprising a pair of vertically arranged inner and outer members forming a liquid passage between them, means for discharging liquid upon the exterior wall of the outer member and the interior wall of the inner member, and means for conducting liquid from the heating chamber of the heating section to the passage between the members of the regenerative section.

20. A pasteurizer comprising a heating section, a regenerative section extending to an elevation higher than that of the heating section, and a member operable within the 5 heating section and having means for agitating the liquid therein and also means for forcibly discharging it into the regenerative section.

In testimony whereof I have hereunto set my hand in presence of two subscribing witnesses. 10
